Sam has over 5 years as a Sales Associate. Sam shows great initiative when it comes to problem solving and team work. He is great at analyzing stock problems and providing various solutions

Interview Notes

Joe Stewart, Manager: Sam seemed nervous when he was interviewed. I'm not sure if this was because he is naturally nervous or if he did not know how to answer the questions that were asked.

Stu Yen, Sr. Manager: Joe, I disagree...Sam was very pleasant to speak with. He was articulate and showed great initiative when he spoke about what he would do as floor manager.

Jose Mendez, Manager: Sam lacked experience in stocking but was very knowledgeable about best organization practices.

Eva Luky, Manager: Sam has very strong skills. He demonstrates great collaboration through prior experience.

Bob Blank, Manager: I could see Sam as a part of my team in the near future.

Lauren White, Manager: Sam is a solid candidate.
